US0D1096793S

(12) **United States Design Patent** (10) Patent No.: **US D1,096,793 S**
 Sayeg et al. (45) Date of Patent: ** Oct. 7, 2025

(54) **DISPLAY SCREEN OR PORTION THEREOF WITH GRAPHICAL USER INTERFACE**

(71) Applicant: **Genesys Cloud Services, Inc.**, Menlo Park, CA (US)

(72) Inventors: **Abigail Sayeg**, Franklin, MA (US); **Daniel Watchorn**, Portmarnock (IE); **Vanessa Ferranto**, Reading, MA (US)

(73) Assignee: **Genesys Cloud Services, Inc.**, Menlo Park, CA (US)

(**) Term: **15 Years**

(21) Appl. No.: **29/932,883**

(22) Filed: **Mar. 15, 2024**

(51) LOC (15) Cl. **14-04**

(52) U.S. Cl.

USPC **D14/485**

(58) **Field of Classification Search**

USPC D14/485-495

See application file for complete search history.

CLAIM

The ornamental design for a display screen or portion thereof with graphical user interface, as shown and described.

DESCRIPTION

The sole FIGURE is a front view of a display screen or portion thereof with graphical user interface showing our new design.

The double peripheral dashed broken lines illustrate a display screen or portion thereof, and form no part of the claimed design. The interior text, icons, and symbols illustrated in broken lines form no part of the claimed design.

1 Claim, 1 Drawing Sheet
